No. 893,117.

PATENTED JULY 14, 1908.

J. A. WANOUS.
TOILET ARTICLE.
APPLICATION FILED AUG. 28, 1907.

Fig. 1.

Fig. 2.

Fig. 3.

WITNESSES:

C. G. Snow.
J. H. Snow

Josie A. Wanous, INVENTOR.
BY Emma G. Wells.

ATTORNEY.

UNITED STATES PATENT OFFICE.

JOSIE A. WANOUS, OF MINNEAPOLIS, MINNESOTA.

TOILET ARTICLE.

No. 893,117.

Specification of Letters Patent.

Patented July 14, 1908.

Application filed August 23, 1907. Serial No. 389,913.

REISSUED

To all whom it may concern:

Be it known that I, JOSIE A. WANOUS, a citizen of the United States, residing at Minneapolis, in the county of Hennepin and State of Minnesota, have invented a new and useful Toilet Article, of which the following is a specification.

My object is to produce a toilet article in convenient shape to be used once, and which will only require the addition of water to prepare it for use; and my invention consists of the novel features herein shown, described and claimed.

In the drawings: Figure 1 is a side elevation of a single package of my toilet article in condition for preservation and shipment, there being a removable covering of oiled paper. Fig. 2 is a side elevation of the package with the covering removed. Fig. 3 shows the article in use.

Referring to the drawings in detail, the hair tonic mixture 4 is inclosed in the porous cloth sack 5, said sack being closed by stitching 6, and the package thus formed is placed in an oil paper covering 7, said covering being closed by a string 8.

In preparing the hair tonic mixture 4, I take about equal parts of bitter apple, camomile, soap bark, and lavender flowers, and mix them thoroughly in a dry state. I then take a small quantity of the dry mixture and place it in a porous cloth sack 5 and seal the sack by stitching 6, and then apply the removable covering. The oiled covering will preserve and confine the odor and other desirable qualities of the mixture for a long time.

When it is desired to use the hair tonic, the covering 7 is removed and water applied to the package which becomes a wet spongy mass saturated with hair tonic, and this mass is used as a sponge in washing and scrubbing the hair and head. A package is intended to be used only once.

The mixture is not only pleasant to use, giving the effect of a shampoo, but it is very beneficial to the hair and scalp.

Thus I produce an article of manufacture comprising a spongy package saturated with hair tonic and adapted to be used as a sponge and shampoo, and apply a preservative covering.

I claim:

A permeable bag normally inclosed within an impervious covering, the said permeable bag serving as a receptacle and as a strainer for a hair tonic mixture, said hair tonic mixture embodying fibrous substances which are adapted to serve as a sponge when the tonic ingredients are extracted, and said impervious covering being adapted to serve as a protection for the said permeable bag and its contents until removed for use, substantially as set forth and for the purposes specified.

JOSIE A. WANOUS.

Witnesses:

LYDIA K. CARLSON,
C. F. SNOW.